(57) **CLAIM**

The ornamental design for semiconductor device, as shown.

DESCRIPTION

FIG. 1 is a top, rear, right side perspective view of a semiconductor device showing our new design;

FIG. 2 is a top view thereof;

FIG. 3 is a bottom view thereof;

FIG. 4 is a one side view thereof;

FIG. 5 is the opposite side view thereof;

FIG. 6 is a rear view thereof; and,

FIG. 7 is a front view thereof.
